ATTORNEY.

UNITED STATES PATENT OFFICE.

MEYER NEWROCK, OF PHILADELPHIA, PENNSYLVANIA.

DESIGN FOR A SESQUICENTENNIAL BADGE.

Application filed April 30, 1926. Serial No. 17,520. Term of patent 3½ years.

To all whom it may concern:

Be it known that I, MEYER NEWROCK, a citizen of the United States, residing at Philadelphia, in the county of Philadelphia and State of Pennsylvania, have invented a new, original, and ornamental Design for Sesquicentennial Badge, of which the following is a specification, reference being had to the accompanying drawing, forming part thereof.

Fig. 1 is a plan view of a sesquicentennial badge, showing my new design.

Fig. 2 is an edge view thereof.

I claim:

The ornamental design for a sesquicentennial badge, as shown.

MEYER NEWROCK.
